(57) **CLAIM**

We claim the ornamental design for a handle for a covering for an architectural opening, as shown and described.

DESCRIPTION

FIG. 1 is a perspective view of a handle for a covering for an architectural opening in accordance with a first embodiment of the present design.

FIG. 2 is a front elevational view thereof.

FIG. 3 is a rear elevational view thereof.

FIG. 4 is a left side view thereof.

FIG. 5 is a right side view thereof.

FIG. 6 is a bottom plan view thereof.

FIG. 7 is a top plan view thereof.

FIG. 8 is a perspective view of a handle for a covering for an architectural opening in accordance with a second embodiment of the present design.

FIG. 9 is a front elevational view thereof.

FIG. 10 is a rear elevational view thereof.

FIG. 11 is a left side view thereof.

FIG. 12 is a right side view thereof.

FIG. 13 is a bottom plan view thereof; and,

FIG. 14 is a top plan view thereof.

The dash-dash broken lines illustrate features of the handle for a covering for an architectural opening that form no part of the claimed design.
